UNITED STATES PATENT OFFICE.

ELLISON EDWARD VANDERHOEF, OF RUTH, NEVADA, ASSIGNOR TO AMERICAN MAN-
GANESSE STEEL COMPANY, OF AUGUSTA, MAINE, A CORPORATION OF MAINE.

DIPPER-BUCKET.

1,208,055.

Specification of Letters Patent. Patented Dec. 12, 1916.

Application filed September 12, 1916. Serial No. 119,652.

To all whom it may concern:

Be it known that I, ELLISON EDWARD VANDERHOEF, a citizen of the United States, and a resident of Ruth, in the county of White Pine and State of Nevada, have made and invented certain new and useful Improvements in Dipper-Buckets, of which the following is a specification.

My invention relates to dipper buckets, 10 and concerns in particular the construction of that portion thereof to which the dipper latch keeper is secured.

In the ordinary type of dipper bucket, the hinged bottom is held in closed position by 15 an unprotected latch keeper which is secured to the front wall of the dipper and projects therebelow. The exposed position of the latch keeper renders it especially liable to breakage as the bucket is oftentimes forcibly 20 dropped to the ground, or forcibly strikes against the side of a car. A further breakage of the latch keeper is caused by using the bucket as an anchorage and drawing the steam shovel or dredge forwardly or rear- 25 wardly thereby, the entire strain in such case being brought to bear upon the latch keeper.

It is therefore an object of my invention 30 to provide a dipper front wherein the latch keeper is housed and protected against injury, and all forces and strains, other than those arising from the securement of the bottom of the bucket in place, are prevented 35 from reaching the latch keeper, and are taken up by parts especially designed to withstand the same.

Other objects and advantages will appear 40 as the description proceeds, wherein it is to be understood that changes may be made 45 in the precise embodiment of the invention, within the scope of what is claimed, without departing from the spirit thereof.

The preferred embodiment of my invention 50 is disclosed in the accompanying drawings, wherein:

Figure 1 is a view in front elevation of a dipper front embodying the characteristic features of my invention; Fig. 2 is a view in vertical cross-section taken on the line 2—2 55 of Fig. 1; and Fig. 3 is a view in perspective of a latch keeper.

Referring specifically to the several views, the dipper front 10 is preferably formed with the thickened lower edge 11, having at 60 its central portion a vertical opening or

recess 12, in which the latch keeper 13 is anchored.

The latch keeper is formed with the lower protruding, and latch-receiving, end 14, and with the attaching plate 15 projecting thereabove, there being a ledge or shoulder 16 extending between the two parts of the latch keeper, and providing for the proper assemblage of the latch keeper within the opening in the dipper front. The latch keeper is anchored to the front by bolts 17 which extend through the reinforced edge of the dipper front and through the attaching plate of the latch keeper. Arranged upon opposite sides of the latch keeper, and supplementing the same, are downwardly projecting lugs 18, the same being formed integral with, and approximating the thickness of, the lower edge of the dipper bucket. These lug members embrace the latch keeper therebetween and project some little distance therebelow, thus completely housing and protecting the latch keeper from injury and preventing the same from being broken should the bucket be forcibly 65 dropped upon a stone, or should the lower edge of the bucket forcibly strike against a car, or by other causes. Furthermore, the dredge or steam bucket may be forcibly moved by driving the latch keeper and lugs 70 forcibly into the ground and using the same for an anchor without danger of distorting or breaking the latch keeper.

What I claim is:—

1. An article of the class described comprising a dipper front, a dipper latch keeper carried thereby and projecting below the lower extremity of said dipper, and means carried by said dipper front and located upon opposite sides of said dipper latch keeper, adapted to protect the same. 75

2. A dipper front provided with spaced and integral lugs projecting below the bottom edge of said front, and a dipper latch keeper secured to said front and positioned between, and protected by, said spaced integral lugs. 80

3. A dipper front having front and side walls, said walls provided with a reinforcing portion extending around the lower extremity thereof, spaced lugs formed integral with said front wall and projecting below said reinforced portion, and a dipper latch keeper secured to said reinforced portion, housed between, and protected by, said lugs. 105 110

4. In combination with the lower extremity of a dipper front, of a latch keeper carried thereby and projecting therebelow, and lugs carried by and projecting below the lower extremity of said dipper front and arranged adjacent said dipper latch keeper and adapted to protect the same.
5. A dipper front with spaced lugs projecting therebelow, a latch keeper secured to said front and protected by said spaced lugs, said latch keeper formed with a lower latch-receiving end, with an attaching plate

projecting thereabove, and with a ledge extending between the attaching plate and the latch-receiving end, said ledge contacting 15 with the lower extremity of said dipper front.

Signed at Ruth, in the county of White Pine and State of Nevada, this nineteenth day of August, A. D. 1916.

ELLISON EDWARD VANDERHOEF.
